(57) **ABSTRACT**

A new *Chrysanthemum* plant named 'CIFZ0119' particularly distinguished by its dark pink and white striped flowers, daisy-type inflorescences, excellent flower production, moderate growth and spreading plant habit, and very uniform flowering with response time of 7 weeks when grown under short days.

1 Drawing Sheet

1

Latin name of the genus and species of the plant claimed:
Chrysanthemum x morifolium.
Varietal denomination: 'CIFZ0119'.

BACKGROUND OF THE NEW PLANT

The present invention comprises a new *Chrysanthemum*, botanically known as *Chrysanthemum x morifolium*, and hereinafter referred to by the variety name 'CIFZ0119'.

'CIFZ0119' is a product of a planned breeding program. The new cultivar has dark pink and white striped flowers, daisy-type inflorescences, excellent flower production, moderate growth and spreading plant habit, and very uniform flowering with response time of 7 weeks when grown under short days.

'CIFZ0119' originates as a natural whole plant mutation discovered among flowering plants of 'CIDZ0100' growing in an outdoor field in Alva, Florida in July 2018. The parent 'CIDZ0100', U.S. Plant Pat. No. 33,369, sold commercially as 'Paisley Park Purple Bicolor', having inflorescences displaying a lower ratio of purple to white stripes under usual conditions, and a greater tendency to fade under hot growing conditions, while it is similar to 'CIFZ0119' in all other characteristics.

The first act of asexual reproduction of 'CIFZ0119' was accomplished when vegetative cuttings were propagated from the initial selection in October 2018 in a greenhouse in Gilroy, California.

BRIEF SUMMARY OF INVENTION

Horticultural examination of plants grown from cuttings of the plant initiated February 2019, and continuing thereafter, has demonstrated that the combination of characteristics as herein disclosed for 'CIFZ0119' are firmly fixed and are retained through successive generations of asexual reproduction.

2

'CIFZ0119' has not been observed under all possible environmental conditions. The phenotype may vary significantly with variations in environment such as temperature, light intensity and day length.

5 A Plant Breeder's Right for this cultivar has not yet been applied for. 'CIFZ0119' has not been made publicly available prior to the effective filing date of this application, notwithstanding any disclosure that may have been made less than one year prior to the effective filing date of this application by the inventor or another who obtained 'CIFZ0119' directly from the inventor.

The following traits have been repeatedly observed and are determined to be basic characteristics of the new variety. The combination of these characteristics distinguishes this 15 *Chrysanthemum* as a new and distinct variety.

BRIEF DESCRIPTION OF THE PHOTOGRAPHS

20 The accompanying photographic drawings shows typical flower and foliage characteristics of 'CIFZ0119' with colors being as true as possible with an illustration of this type.

The whole plant photographic drawing, shown in FIG. 1, was taken in Gilroy, California in May 2024.

25 The close-up view of the inflorescence shown in FIG. 2, was taken in Milton, Ontario, Canada in February 2020 of plants approximately 12 weeks old.

DETAILED BOTANICAL DESCRIPTION

30 The plant descriptions and measurements were taken indoors in Gilroy, California in November 2024 on about 12 week old plants. Unrooted cuttings had been planted, 4 plants per pot, in 6 inch pots in August 2022. The plants were pinched and moved to short days in September 2022 to induce flowering.

35 Color references are made to The Royal Horticultural Society Colour Chart (RHS) 2001.

US PP37,086 P2

5

Length filaments.—0.4 cm.
Anther color.—RHS 1A.
Anther length.—0.1 cm.
Anther shape.—Oval.
Color of pollen.—Absent.
Pollen amount.—Absent.
Fertility/seed set.—Has not been observed to date.

6

Disease/pest resistance.—Has not been observed to date.

What is claimed is:

1. A new and distinct variety of *Chrysanthemum* plant
5 named 'CIFZ0119' substantially as illustrated and described
herein.
